(57) CLAIM

The ornamental design for a garment, as shown and described.

DESCRIPTION

FIG. 1 is a front view of a garment according to a first embodiment of the design;

FIG. 2 is a rear view thereof;

FIG. 3 is a right side view thereof;

FIG. 4 is a left side view thereof;

FIG. 5 is a rear perspective view thereof;

FIG. 6 is a rear view thereof shown in an environment of use;

FIG. 7 is a front view of a garment according to a second embodiment of the design;

FIG. 8 is a rear view thereof;

FIG. 9 is a right side view thereof;

FIG. 10 is a left side view thereof;

FIG. 11 is a rear perspective view thereof;

FIG. 12 is a rear view thereof shown in an environment of use;

FIG. 13 is a front view of a garment according to a third embodiment of the design;

FIG. 14 is a rear view thereof;

FIG. 15 is a right side view thereof;

FIG. 16 is a left side view thereof;

FIG. 17 is a rear perspective view thereof;

FIG. 18 is a rear view thereof shown in an environment of use;

FIG. 19 is a front view of a garment according to a fourth embodiment of the design;

FIG. 20 is a rear view thereof;

FIG. 21 is a right side view thereof;

FIG. 22 is a left side view thereof;

FIG. 23 is a rear perspective view thereof; and,

FIG. 24 is a rear view thereof shown in an environment of use.

The portions of the garment shown in broken lines in FIGS. 1-24 do not form part of the claimed design. The broken line showing of the arms, torso, neck, and head in FIGS. 6, 18, and 24 and of the arms, legs, neck, and head in FIG. 12 is for the purpose of illustrating portions of the environmental structure and forms no part of the claimed design.
